Application for a grant of a patent or a certificate of utility model.

To all whom it may concern,

Be it known that I, FREDK. H. BROWN, a citizen of the United States, residing at Brooklyn, in the county of Kings, and state of New York, have invented, made and constructed the following Improvement in Collar-Lock and Joint:

This invention relates to ~~either~~ to a device which it has for an object the provision of a 10 devices for the locking or clamping together of parts to be temporarily held for further operation, or for the locking together of parts permanently.

Another object of this invention is to produce a collar-block which may be put into effective use quickly and readily, one which, though analogous to the more expensive and already patented and of which I am fully aware, may be manufactured with a great reduction in the cost; one which obviates the use of wrenches or the like in its application.

The bolts or the like with which the device as a whole is locked, does not when being applied for the holding together of parts, subject the bolt to any twisting strain which usually causes a bolt to break, but a straight or longitudinal pull on the bolt is always had. It is manifest therefore, that 25 a thoroughly effective collar lock is the subject matter of this invention.

With these and other objects in view, the invention consists in the novel utilization and in some parts improvement of the combination of elements.

Reference characters of the following specification correspond with like parts in the drawing which forms a part of the specification and in which:

40 Figure 1, is a sectional view of the upper parts of my invention being shown in section. Fig. 2, is a horizontal section taken on the line 2--2, Fig. 1. Fig. 3, is a perspective view of the semi-cylindrical bushings which form a part of my invention. Fig. 4, is a perspective view of the U shaped wedge.

The numeral 1, designates a bolt, and 50 is my intention to utilize plain or threaded bolts.

The numeral 2, designates a disk or end
jar, having an interiorly tapered opening
therein. I also provide two semi-cylindrical
bushings 4, the said bushings are externally
tapered to correspond to the interior tapers
of the opening 3 of the collar and they
are secured to the

He had a difficult and dissatisfied life at first, but he soon became a good man. The harder he worked, the more he learned, the more harder he worked. The more he learned, the more he worked, and so on.

The ridge of the wall of the upper 80
concreted canal, which stands on the bed
of the stream, with the bottom of the 80
valley, deviated to correspond with the upper
course of the old stream. The present
depth of the stream. As the ridge is
stepped down, the valleys are exposed to
erosion, particularly and relatively to the last 80
valley, so that the bed of the stream is in
connection with the ridge.

As specimens were mentioned the hardlings were collected and when able to refer them to one of the local areas, the species were determined. A small area of the forest was used for the first 1000 specimens, but eventually expanded to a larger area, but the first 1000 specimens were collected in the same area.

Mark 13:34 shows that I deserved the previous judgment of my invention. I too was to be condemned to eternal changes and variation within the scope of the invention as defined by the scope of the unpatented claims.

It is considered as important to have a good
knowledge of the language of the country in
which one is to do business.

106
The following is a list of the species of *Trichostema* which have been collected in the State of California. The list is not complete, as many species have not been collected. The list is arranged in alphabetical order, and the names of the species are given in the following order: Genus, species, and variety.

posite sides of a bolt or the like; and a locking device correlated with the collar to impart relative movement between the said collar and said bushings, as and for the purpose described.

2. A collar-lock adapted for use with a bolt or the like having an abutment at one end thereof, consisting of a collar having an interiorly tapered opening therein, semi-cylindrical bushings being externally tapered and internally roughened and adapted to be arranged within the interiorly tapered opening in said collar at opposite

sides of a bolt or the like; and a U shaped wedge correlated with the collar to impart relative movement between the said collar and said bushings, there being teeth on upper and inner faces of the branches of said wedge as and for the purpose described.

In testimony whereof I affix my signature in presence of two witnesses.

FRANK H. HOPKINS.
